LUTHER J. KINNARD, OF CHICAGO, ILLINOIS, ASSIGNOR TO WESTINGHOUSE ELECTRIC
ELEVATOR COMPANY, A CORPORATION OF ILLINOIS

ELEVATOR CONTROL SYSTEM

Application filed October 6, 1928. Serial No. 310,714.

My invention relates to motor-control systems and has particular relation to control systems for elevators, hoists and the like.

An object of my invention is to provide a control system for elevators wherein an elevator car may be variously controlled to operate economically in an installation requiring floor-to-floor service.

Another object of my invention is to provide a control system for elevators of the type used in department stores wherein the car may be automatically slowed down as it approaches each of the floors, but will not be stopped thereat unless passengers desire to enter or leave the car.

Another object of my invention is to provide a control system wherein an emergency stop may be made by momentary reversal of the car switch.

Another object of my invention is to provide a control system for elevators of the automatic-landing type wherein, when a passenger signifies his intention to enter or leave the car at a floor in case the car is too close to the floor to be stopped accurately thereat, the car may be reversed to make an automatic landing at that floor from the opposite direction.

Elevator service in a department store differs from that required in most other elevator installations in that the car is normally required to stop at every floor on each trip. Systems have been devised for this class of service in which the car, when started, automatically stops at the next floor, whether actual service is desired at that floor or not, and hence such prior systems are uneconomical because a large amount of time is wasted in making the complete stop and in opening the doors only to find that there are no passengers desiring to board or leave the car at those floors.

It has been discovered that a more economical manner of operating department-store elevators is to cause the car to momentarily slow down at each of the floors, thus preparing the car to make a stop, if it is desired. This operation gives the attendant a considerably lengthened period during which he may receive notification of the intentions

of the passengers on his car as to their desires to leave the car at the floor then approached by the car. On the other hand, if, during the period of slow operation, no persons desire to board or leave the car, the car will then automatically accelerate to a higher speed and again decelerate as it approaches the next floor.

On the other hand, there may be occasions when it is desired to cause the car to make stops only at certain of the floors and, under those conditions, it is not desirable to slow down the car except when it approaches the desired floors.

I have, therefore, provided a control system which may be operated in either of two manners, (1) in which the car will travel at the highest speed with which floor-to-floor runs may be made and in which the car will automatically slow down as it approaches each of the floors and (2) in which the car will be operated at a higher speed and will only be slowed down at those floors at which the attendant desires to stop.

My invention will be described with reference to the accompanying drawing in which:

The sole figure is a diagrammatic illustration of an elevator car embodying my department-store control system.

Referring to the drawing, I have illustrated an elevator car C suitably suspended upon a cable Ca which passes over a hoisting drum D to a suitable counter-weight Cw. The hoisting drum D is directly coupled to the armature EM' of an elevator motor EM.

I have illustrated the control for the elevator motor EM as being of the variable-voltage type, wherein the armature EM' of the motor EM is connected in loop circuit with the armature G' of a generator G. The generator G is provided with a separately-excited-field winding GF, a series-field winding GSF and a demagnetizing-field winding GAF. The armature G' of the generator G is suitably driven by means of a driving motor M, illustrated as of the shunt-wound type having its armature M' and its field winding MF connected in shunt relation to a source of power designated by line conductors L1.

and L2. The elevator motor EM has its field winding EMF connected for constant-voltage energization to supply conductors L1 and L2.

5 The direction and speed of operation of the motor EM is suitably controlled by controlling the direction and value of excitation current supplied to the generator-separately-excited-field winding GF.

10 The direction of excitation current for field winding GF is suitably controlled by means of an up-direction switch 1 and down-direction switch 2, while the value of the current supplied to the field winding is controlled by means of an intermediate-speed relay 3 and a high-speed relay 4.

15 The operation of the up-direction and down-direction switches 1 and 2 are suitably controlled by means of up-direction and down-direction relays 5 and 6, respectively.

20 A car switch CS, mounted upon the elevator car C to be actuated by an attendant on the car, may be utilized to control the direction and speed relays.

25 A control system of any suitable type may be employed for automatically stopping the car C level with the floors past which it moves, though I have illustrated the control system as of the automatic-inductor-landing type such as is disclosed in the co-pending application of E. M. Bouton, Serial No. 731,921 filed August 14, 1924, and assigned to the Westinghouse Electric and Manufacturing Company.

30 The inductor-landing system includes a stopping inductor relay S, an up-intermediate-speed inductor relay SU and an up-high-speed inductor relay HU for causing the car to be automatically decelerated from its intermediate and high speeds respectively, and brought to a stop at an exact level with a floor when the car is traveling upwardly. Similarly, stopping inductor relay S' down-intermediate-speed inductor relay SD and down-

35 high-speed inductor relay HD will cause the car to slow down and stop at the floors when the car is traveling downwardly. It is assumed that each of the floors past which the car moves will be provided with a set of inductor plates cooperating with the inductor relays as the car approaches predetermined points in advance of the corresponding floors.

40 I have illustrated the inductor plates associated with the second floor as comprising a stopping inductor plate S', an up-intermediate-speed inductor plate SU' and an up-high-speed inductor plate HU' for successively operating inductor relays HU, SU and S as the car, moving upwardly, approaches the second-floor level, indicated by the dotted line. When the car is traveling downwardly, intermediate-speed inductor plate SD' and high-speed inductor plate HD' will successively operate inductor relays HD and SD,

respectively, as the car approaches the second-floor level.

45 My system will best be understood with reference to an assumed operation. Assuming the car C to be at the lowermost floor, the attendant may start the car upwardly by moving the car switch in a clockwise direction. Such operation will cause closing of the elevator gate and the hatchway door at the first floor (not shown) in any well known manner, if it is desired that such doors and gate be automatic in operation and in addition such movement of the car switch will cause energization of up-direction relay 5 by way of a circuit which extends from line conductor L1 through conductors 10, 11 and 12, the coil of up-direction relay 5, conductor 13, contact members 14, 15 and 16 on car switch CS and conductor 17 to line conductor L2.

50 Actuation of up-direction relay 5 completes a circuit which energizes up-direction switch 1 and extends from line conductor L1, through conductor 18, normally closed contact members 19 of stopping inductor relay S, conductors 20 and 21, the coil of up-direction switch 1, conductor 22, contact members b on up-direction relay 5, conductor 23, normally-closed contact members a of a voltage relay V and conductor 24, to line conductor L2.

55 Up-direction switch 1, when energized, completes a self-holding circuit for itself which extends from line conductor L1 to the coil of up-direction switch 1 by way of conductors 18, 20 and 21, as previously traced, and thence, by way of conductor 25, contact members a of up-direction switch 1, conductor 26, normally closed contact members a on down-direction relay 6 and conductors 27, 28 and 24, to line conductors L2. Thus, it will be observed that the up-direction switch will remain in operating position until inductor relay S is actuated to open its contact members 19.

60 Up-direction switch 1, when actuated, also completes a circuit for supplying excitation current to the separately-excited-field winding GF of the generator G, which circuit extends from line conductor L1, through conductors 10 and 29, contact members b on up-direction switch 1, conductor 30, field winding GF, conductors 31 and 32, contact members c on up-direction switch 1, conductor 33, resistors 34 and 35 and conductor 36, to line conductor L2. The car C will, therefore, be started upwardly at a very low speed.

65 Should it be desired to cause the car to travel at a greater speed, the car switch CS may be moved to a further position in a clockwise direction to complete a circuit for intermediate-speed relay 3, which extends from line conductor L1, through conductors 37, contact members 38 on down-intermediate-speed inductor relay SD, conductor 39, contact members 40 on up-intermediate-

speed inductor relay SU, conductor 41, the coil of intermediate-speed relay 3, conductor 42, contact members *b* on relay V, conductors 43 and 44, contact members 45, 15 and 16 on car switch CS and conductor 17, to line conductor L2. Intermediate-speed relay 3, when energized, closes its contact members *b* to shunt resistor section 34 from the circuit previously traced for field winding GF 10 to thereby cause the car to travel at a higher speed and also closes its contact members *a* to complete a self-holding circuit for itself independent of car switch CS and relay V which circuit extends, as previously traced, 15 from line conductor L1, through the coil of intermediate-speed relay 3 and thence extends, by way of conductors 42 and 46, contact members *a* on intermediate-speed relay 3 and conductor 47, contact members *f* on up-direction switch 1, and conductor 48 to line conductor L2.

The value of field excitation supplied to the separately excited field winding GF, when intermediate-speed relay 3 is energized, 20 should be so selected as to produce the highest practicable speed with which the car C may make a floor-to-floor run. In practice, it is found that a speed of approximately 300 feet per minute is the most rapid speed 25 to which acceleration and from which deceleration may be made with a minimum of discomfort to passengers. Under our assumed conditions, the car will approach the second floor at the above named rate of 30 speed.

It will be observed that the car switch CS has, in addition to contact segment 15, a segment 49 electrically connected thereto and so arranged that, when the car switch CS 40 has been moved just sufficiently far to engage contact segment 15 and contact member 45, contact segment 49 will be in engagement with contact member 50 but will be out of engagement with contact member 51. 45 Hence, under our assumed operating condition, with a car switch moved to produce intermediate speed, a circuit will be completed for energizing intermediate-speed inductor relay SU. This circuit extends from 50 line conductor L1, through conductors 10 and 52, contact members *e* on up-direction switch 1, conductor 53, the coil of up-intermediate-speed inductor relay SU, conductors 54, 55, 56 and 57, contact members 50, 55 49, 15 and 16 on car switch CS and conductor 17, to line conductor L2.

As the car approaches the second floor, with the coil of inductor relay SU energized, relay SU will be brought adjacent to inductor relay plate SU' to thereby cause it to open its contact members 40 during the time the relay is passing its inductor plate.

The opening of contact members 40 on relay SU deenergizes the holding circuit for 65 intermediate-speed relay 3 and causes de-

energization of this relay to automatically slow down the car. Hence, the car will approach the second floor at a slow speed. If it is desired to stop the car at the second floor, the attendant must center the car 70 switch, which operation causes energization of the coil of stopping inductor relay S by way of a circuit which extends from line conductor L1, through conductor 58, the coil of stopping inductor relay S, conductor 59, contact members 51, 49, 15 and 16 on car switch CS and conductor 17, to line conductor L2. Hence, as the car approaches the level of the second floor, the relay S will be brought adjacent to inductor plate S', thus causing inductor relay S to open its contact members 19 to break the holding circuit for the up-direction switch 1.

On the other hand, if the attendant has not been notified that passengers wish to leave the car at the second floor and he observes that no one desires to board the car at the second floor, he may maintain the car switch in a position to engage contact member 45, and the car will again accelerate to intermediate speed.

It will be observed that the energizing circuit of intermediate-speed relay 3 extends through normally closed contact members *b* on relay V. If relay V is so selected as to open its contact members only while the car is above the landing speed, that is, the speed determined by the inclusion of both resistor sections 34 and 35 in the field winding circuit, it will be observed that, if the car has slowed down to landing speed, the energizing circuit for intermediate-speed relay 3 will again be closed through conductors 42, 43 and 44 and contact member 45 of car switch CS. However, as soon as the car accelerates to a speed above the land speed relay V opens its contact members and places relay 3 under the exclusive control of the inductor relays SU and SD.

With the above construction, each time the car approaches a floor with the car switch held in intermediate-speed position, the car will be automatically slowed down but will not be stopped so long as the car switch is held in this position, and the car will again accelerate to move to the next floor, when the inductor relay SU or SD passes out of cooperative relation with its associated inductor plate.

Assuming that a passenger desired to leave the car at the second floor, but did not inform the attendant of his intention until after the car had slightly passed the second floor level, the attendant may reverse the car switch causing the car to reverse its direction of travel and bring the car back to the floor from the opposite direction. Movement of the car switch to reverse position will complete a circuit for energizing down-direction relay 6, by way of a circuit which extends 120 125 130

from line conductor L1, through conductors 10, 11 and 60, the coil of up-direction relay 6, conductor 61, contact members 62, 15 and 63 on car switch CS and conductors 64 and 17, to line conductor L2.

Energization of down-direction relay 6 opens its contact members *a* to open the holding circuit for up-direction switch 1, and up-direction switch 1 when deenergized, opens its contact members *f* to break the holding circuit for speed relay 3. Hence, the car will be stopped immediately. If the car switch CS is held in the new position until relay V is deenergized by the reduction in speed of the motor EM, a circuit will be completed by relay 6 for energizing down-direction switch 2, which extends from line conductor L1, through conductor 18, contact members 19 on stopping inductor relay S, conductors 20 and 65, the coil of down-direction switch 2, conductor 66, contact members *b* on down-direction relay 6, conductors 67 and 23, contact members *a* on relay V and conductor 24, to line conductor L2. Hence, the car will start downwardly at slow speed.

If the car switch CS is moved into engagement with contact member 68, intermediate-speed relay 3 will again be energized by way of conductor 43, as previously traced, and the car will move back to the second-floor level at intermediate speed.

It will be observed, therefore, that if the car switch is held in the reverse position, the car will be reversed, but a momentary actuation of the car switch to reverse position merely causes deenergization of intermediate-speed relay 3 and the direction switch which has been in operation but will not cause completion of circuits necessary to reverse the car. This latter operation is important in that a momentary reversal of the car switch will act as an emergency-stop operation.

If, on the other hand, it is desired that the car should not slow down at each floor approached thereby, the car switch may be moved to a continuous running position its extreme position in either direction to thereby energizing high-speed relay 4 and moving contact segment 49 out of engagement with either of contact members 50 and 50'. Movement of segment 49 out of engagement with contact members 50 and 50' prevents closure of the energizing circuit for the coils of intermediate-speed inductor relays SU or SD, so that these relays will not operate when they pass the corresponding inductor plates SU' and SD' mounted adjacent the various floors. In addition, when the car is not to be stopped or slowed down at each floor, it is desirable that it should be permitted to travel at a higher speed than 300 feet per minute and hence, with the car switch in the continuous running position, a circuit for high-speed relay 4 may be traced from line conductor L1, through conductors 37 and 69, contact

members 70 on down-high-speed-inductor relay HD, conductor 71, contact members 72 on high-speed-up inductor relay HU, conductor 73, the coil of high-speed relay 4, conductors 74 and 75, contact members 76, 15 and 16 on car switch CS and conductor 17, to line conductor L2.

As was described with reference to intermediate-speed relay 3, it will be observed that, upon actuation of high-speed relay 4 its contact members *v* will shunt resistor section 35 from the field winding circuit, and its contact members *a* will complete a self-holding circuit for itself which extends from line conductor L1 through the coil of high-speed relay 4, as previously described, to conductor 74, and thence, by way of contact members *a* on high-speed relay 4 and conductors 77 and 47 contact members *f* on up-direction switch 1 and conductor 48, to the conductor L2.

It will be observed, therefore, that I have provided a control system for department-store elevators wherein a rapid floor-to-floor movement may be had with automatic deceleration at each of the floors to provide ample opportunity for the attendant to stop the car at each of the floors, if so desired, and which, on the other hand, may be operated at a greater speed whenever it is desired to travel more than one floor at a time. In addition to this, it will be further observed that I have provided a system of control in which, if the passengers do not indicate their intention to enter or leave the car until after the car has passed the floor, the car may be readily reversed to give the necessary service. In addition to the foregoing, I have also provided a ready "emergency stop" control by actuation of the car switch in the reverse direction to that in which the car is traveling when such stop is desired.

It is understood that the described embodiment of my invention is illustrative only and I do not desire to be limited to the details shown herein except as defined in the appended claims.

I claim as my invention:

1. In a control system for a department-store elevator, a car operable past a plurality of floors, means for starting said car in either direction and movable from a car-stopping position to a car-running position, means operable when said starting means is in said running position for causing said car to momentarily slow down as it approaches each floor, and means operable upon movement of said starting means to car-stopping position for causing said car to stop at the next floor thereafter approached by said car.

2. In a control system for a department-store elevator, a car operable past a plurality of floors, means for starting said car in either direction and movable from a car-stopping position to a first car-running position and

to a second car-running position, means operable when said starting means is in said first running position for causing said car to momentarily slow down as it approaches each floor, and means operable upon movement of said starting means to said second running position for causing said car to travel past said floors at a constant speed.

3. In a control system for a department-store elevator, a car operable past a plurality of floors, means for starting said car in either direction and movable from a car-stopping position to a first car-running position and to a second car-running position, means operable when said starting means is in said first running position for causing said car to momentarily slow down as it approaches each floor, means operable upon movement of said starting means to said second running position for causing said car to travel past said floors at a constant speed, and means operable upon movement of said starting means to car-stopping position for causing said car to stop at the next floor thereafter approached by said car.

4. In a control system for an elevator operable past a plurality of floors, means for each floor for decelerating said car as it approaches the corresponding floor, means for each floor for stopping said car when it arrives level with the corresponding floor, means for starting said car, variously operable to cause said car to approach each of said floors subject to control by only the decelerating means for the corresponding floor or to cause said car to approach each of said floors subject to control by both said decelerating means and said stopping means.

5. In a control system for a car operable past a floor, means for said floor for decelerating said car as it approaches said floor, means for said floor for stopping said car when said car is level with said floor, means for controlling the direction of movement of said car, and means, operable when said car is moving in one direction, for immediately stopping said car upon actuation of said direction controlling means to reverse the movement of said car, and means for preventing reverse movement of said car.

6. In a control system for a car operable past a floor, means for said floor for decelerating said car as it approaches said floor, means for said floor for stopping said car when said car is level with said floor, means for controlling the direction of movement of said car, and means operable when said car is moving in one direction for immediately stopping said car upon momentary actuation of said direction controlling means to reverse the movement of said car, and operable upon continued actuation of said direction-controlling means to reverse said car for causing said car to move in the opposite direction.

65 7. In a control system for an elevator op-

erable past a plurality of floors, means for each floor for decelerating said car when it approaches the corresponding floor, means for each floor for stopping said car when it arrives level with the corresponding floor, a 70 car switch, movable to one position for causing said car to approach each of said floors subject to control by only the decelerating means for said floors and movable to another position for causing said car to travel subject to control by both said decelerating means and said stopping means.

8. In a control system for an elevator operable past a plurality of floors, means for each floor for decelerating said car when it approaches the corresponding floor, means for each floor for stopping said car when it arrives level with the corresponding floor, a car switch movable to one position for starting said car and for rendering only said decelerating means effective, operable to another position for rendering both said decelerating means and said stopping means effective, and operable to a third position to render both said decelerating means and said stopping means ineffective.

9. In a control system for an elevator, a car operable past a plurality of floors, means for starting said car in either direction movable from a car-stopping position to a car-running position, means operable when said starting means is in said running position to cause said elevator to decelerate from said running speed to a lower speed when said elevator is one predetermined distance in advance of said floor and operable to cause said elevator to accelerate to said running speed when said elevator reaches a lesser predetermined distance in advance of said floor.

10. In a control system for an elevator, a car operable past a plurality of floors, means for starting said car in either direction and movable from a car-starting position to a car-running position, control means movable to two positions and effective, when in one position, to limit said car speed to a speed lower than said running speed and effective, when in said other position, to cause said elevator to increase said car speed to said running speed, and means effective when said starting means is in said running-speed position to cause said control means to move to said first named position momentarily when said elevator is a predetermined distance in advance of any one of said floors.

11. In a control system for an elevator car operable past a plurality of floors; motive means for said car; and a controller for said motive means, said controller including a starting switch operable from an initial position to a second position, switching mechanism responsive to operation of said starting switch to said second position for causing said motive means to start and accelerate said car to a normal speed, means to cause said motive

means to retard and stop said car at any floor, said means including switching mechanism for causing retardation of said motive means each time said car reaches a point a predetermined distance in advance of a floor and adapted to cause said motive means to again accelerate said car to said normal speed when said car reaches another point a lesser predetermined distance in advance of that floor; and additional switching mechanism adapted upon return of said starting switch to said initial position to render said retarding switching mechanism ineffective to cause said motive means to again accelerate said car to said normal speed and to cause said motive means to stop said car.

12. In a control system for an elevator car operable past a plurality of floors; motive means for said car; and a controller for said motive means, said controller including a starting switch operable from an initial position to a second position, switching mechanism responsive to operation of said starting switch to said second position to complete circuits to cause said motive means to start and accelerate said car to a normal speed, means to cause said motive means to retard and stop said car at any floor, said means including switching mechanism to cause a momentary interruption of said accelerating circuits each time said car approaches a floor, and additional switching mechanism adapted upon return of said starting switch to said initial position to prevent recompletion of said accelerating circuits and to cause interruption of said starting circuits to thereby stop said car.

13. In a control system for an elevator car operable past a plurality of floors; motive means for said car; and a controller for said motive means, said controller including a starting switch operable from an initial position to close starting and running contact members, switching mechanism responsive to the operation of said starting switch to close said starting contact members for causing said motive means to start and accelerate said car to a normal speed, means to cause said motive means to retard and stop said car at any floor, said means including switching mechanism to cause retardation of said motive means each time said car approaches a floor, and additional switching mechanism adapted upon return of said starting switch to said initial position to cause said motive means to stop, and means responsive to closure of said running contact members to render said retarding and stop switching mechanism ineffective.

14. In a control system for an elevator car operable past a plurality of floors; motive means for said car; and a controller for said motive means, said controller including a starting switch operable from an initial position to close starting and running contact

members, switching mechanism responsive to the operation of said starting switch to close said starting contact members for causing said motive means to start and accelerate said car to a normal speed, means to cause said motive means to retard and stop said car at any floor, said means including switching mechanism to cause retardation of said motive means each time said car approaches a floor, and additional switching mechanism adapted upon return of said starting switch to said initial position to cause said motive means to stop, and means responsive to closure of said running contact members to render said retarding and stop switching mechanism ineffective and to cause said motive means to accelerate said car to a higher speed.

15. In a control system for an elevator car operable past a plurality of floors; motive means for said car; and a controller for said motive means, said controller including a starting switch operable from an initial position to close starting and running contact members, switching mechanism responsive to operation of said starting switch to close said starting contact members to cause completion of circuits to cause said motive means to start and accelerate said car to a normal speed, means to cause said motive means to retard and stop said car at any floor, said means including switching mechanism to cause interruption of said accelerating circuits each time said car approaches a floor, and additional switching mechanism adapted upon return of said starting switch to said initial position to cause interruption of said starting circuits to bring said car to rest at said floor, and means responsive to closure of said running contact members to render said retarding and stop switching mechanism ineffective.

16. In a control system for an elevator car operable past a plurality of floors; motive means for said car; and a controller for said motive means, said controller including a starting switch operable from an initial position to close starting and running contact members, switching mechanism responsive to operation of said starting switch to close said starting contact members to cause completion of circuits to cause said motive means to start and accelerate said car to a normal speed, means to cause said motive means to retard and stop said car at any floor, said means including switching mechanism to cause interruption of said accelerating circuits each time said car approaches a floor, and additional switching mechanism adapted upon return of said starting switch to said initial position to cause interruption of said starting circuits to bring said car to rest at said floor, and means responsive to closure of said running contact members to render said retarding and stop switching mecha-

nism ineffective and to cause said motive means to accelerate said car to a higher speed.

17. In an elevator control system, an elevator car operable past a plurality of floors; motive means for said car; decelerating means for controlling said motive means to decelerate said car when said car approaches each of said floors; stopping means for controlling said motive means to stop said car at each of said floors; means for rendering said decelerating means effective to the exclusion of said stopping means; and means for rendering both said decelerating means and said stopping means effective.

18. In an elevator control system, an elevator car operable past a plurality of floors; motive means for said car; decelerating means for controlling said motive means to decelerate said car when said car approaches each of said floors; stopping means for controlling said motive means to stop said car at each of said floors; means for controlling said motive means to the exclusion of said decelerating means and said stopping means; means for rendering said decelerating means effective to the exclusion of said stopping means; and means for rendering both said decelerating means and said stopping means effective.

In testimony whereof, I have hereunto sub-
scribed my name this tenth day of Septem-
ber, 1928.

LUTHER J. KINNARD.
